ARCH-SUPPORTING SHOE

Perley Irving Watts, Rockland, Mass., assignor
of one-half to Edmond A. Hebert, Brookville,
Mass.

Application December 4, 1937, Serial No. 178,021

2 Claims. (Cl. 36—8.5)

This invention relates to shoes designed to support the arch of the foot in such a manner as to prevent the falling of the arch and to give to the wearer a balanced tread. In order to get the proper support, the transverse arch of the foot should have a rigid member in the shoe extending from the heel to the ball portion to carry the weight of the wearer and to prevent sagging of the shank portion of the shoe.

According to the present invention, a rigid member of this kind is provided, and a resilient cushion is built up thereon extending across the shank portion of the shoe, that is, immediately beneath the transverse arch of the wearer's foot, so as to provide an elevated resilient cushion under the cuneiform and cuboid bones. This takes the strain off the main bony arch of the foot but provides for enough resilience under the key-bones of the arch to avoid concentration of pressure at any one point and to give a degree of springiness to the balance tread.

An embodiment of the invention is hereinafter described, and is illustrated on the drawing of which

Figure 1 is a perspective view of a cushion pad for use in my improved shoe.

Figure 2 is a fragmentary bottom plan view of a partly finished shoe embodying the invention.

Figure 3 is a section on the line 3—3 of Figure 2.

Figure 4 is a section on the line 4—4 of Figure 3.

Figure 5 is a fragmentary sectional view of a modified form of cushion pad.

In making a shoe according to the present invention, the innersole 10 and the upper 12 are lasted upon a wooden last 14 in the usual manner. The rib or inseam 16 where the welt 18 is secured to the innersole along the edges of the ball and shank portions of the shoe, and the inturned margins 19 of the upper around the heel, define the bottom cavity of the shoe. When the shoe is ready to have the bottom cavity filled with bottom filler in the usual manner, a cushion 20, such as is illustrated in Figure 1, may be fitted into the heel and shank portions of the bottom cavity as indicated in Figure 2. This cushion may be made of sponge rubber, felt, or any other suitable soft, resilient material. The cushion is characterized by an area 22 of substantially greater thickness than the remainder of the cushion. This area extends transversely from edge to edge of the cushion and is located so as to come in the middle of the shank of the shoe

and under the transverse arch of the foot of the wearer. In assembling the shoe, the cushion pad 20 may be placed in the bottom cavity of the shoe as shown, the pad being held in place by a rigid shank stiffener 24 which is superposed on the pad 20 and which preferably extends from the heel portion of the cavity to the ball portion thereof. The shank stiffener illustrated on the drawing is of a kind which is in common use and consists of a steel plate 26 to which is secured a piece of sheet fiber 28. The steel piece 26 is narrow at the heel end and is provided with a hole through which a tack 30 is driven into the innersole 10 so as to anchor the shank stiffener and the cushion pad 20 to the innersole. The mid-portion of the steel piece 26 is slightly bent transversely to increase the stiffness of the piece, as indicated in Figure 4.

After the cushion pad 20 and shank stiffener 24 have been secured in the bottom cavity of the shoe by the tack 30, the remaining spaces in the cavity are filled with shoe filler in the usual manner so as to fill the cavity completely. The outer sole and heel (not shown) are then secured in place in the usual manner to complete the shoe. When the completed shoe is worn, the forward end of the steel shank piece 26 is supported by the outer sole of the shoe and its rear end is supported by the heel. The thick portion 22 of the pad rests on the mid-portion of the shank piece 26 and forms a local lump which raises a broad ridge of slight but sufficient height across the innersole beneath the middle of the arch of the foot to prevent sagging of the arch.

Instead of the one-piece molded cushion pad shown in Figure 1, an equivalent pad may be more cheaply made, as indicated in Figure 5, by mounting a piece 40 of resilient material such as sponge rubber upon a larger piece 42 having a contour similar to that of the pad 20. In this case, the piece 40 is preferably of the same size as the thickened portion of the pad 20 and is mounted upon the piece 42 so as to form a portion of additional thickness equivalent to the thickened portion 22 shown in Figure 1.

It is evident that various modifications and changes may be made in the particular embodiments of the invention herein shown and described without departing from the spirit or scope thereof as defined in the following claims.

I claim:—

1. In a shoe having an innersole, a rigid shank-piece extending from the heel to the ball portion of the shoe, and a resilient cushion between said shank piece and innersole from the heel of the

shoe to the forward end of the shank portion, said cushion having a portion of extra thickness extending across said shoe at the middle of the shank and raising a broad transverse ridge in the innersole.

5. 2. In a shoe having an innersole and an outer sole, a rigid shank stiffener between said soles extending from the heel of the ball portion of

the shoe and secured to the heel portion of the innersole, and a pad between said shank stiffener and innersole, said pad having an area of maximum thickness at the middle of the shank and forming a transverse ridge in the innersole at the middle of the shank when the shoe is removed from the last.
